UNITED STATES PATENT OFFICE.

WILLIAM VERNAL COATE, OF CELINA, OHIO.

AUTOMATIC DAMPER.

1,255,709.

Specification of Letters Patent.

Patented Feb. 5, 1918.

Application filed March 9, 1917. Serial No. 153,632.

To all whom it may concern:

Be it known that I, WILLIAM VERNAL COATE, a citizen of the United States, residing at Celina, in the county of Mercer and State of Ohio, have invented certain new and useful Improvements in Automatic Dampers, of which the following is a specification.

This invention relates to automatic dampers and its object is to provide a device of novel and simple construction which may be easily adjusted and which, when properly applied, will maintain a desired degree of heat within a heating plant. The invention seeks to provide an arrangement whereby the working parts will be prevented from injury through accidental blows and may be accurately adjusted when desired.

The invention is illustrated in the accompanying drawings and resides in certain novel features which will be hereinafter first fully described and then more particularly pointed out in the claims following the description.

Figure 1 is a front elevation of the apparatus;

Fig. 2 is a similar view of the casing;

Fig. 3 is a vertical section of the casing, the damper plate being shown removed and in edge elevation;

Fig. 4 is a vertical section of the complete apparatus;

Fig. 5 is a horizontal section;

Fig. 6 is a detail group perspective of the dial and the parts co-operating therewith;

Fig. 7 is a detail view of the observation door.

In carrying out my invention, I provide a casing 1 which is of a suitable shape to permit the necessary oscillation of the damper and the parts immediately adjacent the same and also to provide a continuous passage through the casing and the abutting members of the smoke pipe or flue.

The upper end of this casing is circular to fit within an upper section of the smoke pipe and is provided with an external bead or shoulder 2 to prevent buckling of the joint while the lower end of the casing fits over a lower section of the smoke pipe and is provided with an internal rib or bead 3 to prevent buckling and also to form a support resting on the edge of the smoke pipe section. One side of the casing is flattened

and shaped to provide an angular frame 4 upon which is fitted a convex hood 5. The side walls 6 of the frame 4 diverge outwardly, as shown most clearly in Fig. 5, so that when the hood is slid downwardly in engagement with the sides of the frame, the parts will fit tightly so that the hood can not fall away from the casing, it being understood that the hood is constructed with correspondingly formed portions to effect a dovetailed engagement with the walls 6. To attain this result, the side edges of the hood are provided with inwardly extending webs or flanges 7 which bear against the flattened portions of the casing which define the frame 4. At the inner edges of the webs or flanges 7 are outwardly diverging ribs 8 which engage the walls 6 of the frame 4, as shown clearly in Fig. 5. The lower end of the hood is open, as shown at 9, and may be readily engaged over the upper end of the frame 4 so that the hood may be slid downwardly into position. The downward movement of the hood is limited by a transverse internal shoulder 10 which engages and rests on the top 11 of the frame 4 and thereby supports the hood as will be readily understood on reference to Fig. 4. The hood is provided at its center with a glazed swinging door 12 so that the dial of the damper may be easily read and access thereto may be easily had when it is necessary to manipulate the same.

The frame 4 is open to accommodate the damper plate 13 and the walls of the opening are inclined inwardly and downwardly, as shown at 14, so that when they are engaged by the top, bottom and side beveled edges of the damper plate, inward movement of the damper plate will be arrested. The side edges of the damper plate are reduced below their centers to provide shoulders 15 and these shoulders are beveled to produce a knife edge adapted to rock upon the bearings or shoulders 16 upon the sides of the opening in the frame 4, as will be readily understood. It will be seen at once that this arrangement supports the damper so that it may rock very easily and, consequently, will be very sensitive to variations in the draft and to variations in the adjustment of the controlling weight or dial. Projecting inwardly from the inner or rear face of the damper is a governor bar or rod 17 which is preferably made integral with the damper

and has its extremity or free end expanded in a disk-like form to acquire weight, as shown at 18, whereby said arm will tend to hold the damper in a vertical position. An opening 19 through the member 18 increases the radiating surface of the bar and so tends to prevent the holding of heat in the bar. Projecting from the front or outer face of the damper is a shaft 20 having a thread or spiral bead 21 formed thereon and also being constructed with a longitudinal groove 22, as shown. The dial or regulating plate 23 is fitted upon the shaft 20 and is provided with a groove 24 in its bore to engage the bead 21 on the shaft 20, as will be readily understood. The dial is provided with a knob or lug 25 to facilitate its rotation and also to limit its movement to one complete revolution by engaging with the hand or pointer 26 which is disposed in front of the dial and bears normally against the same. The dial is provided around its edge with graduations 27 and the end of the hand or indicator 26 is arranged to ride over said 25 graduations. It will be noted that the dial is of a conical formation and the indicator is, therefore, disposed at an angle to the shoe 28 by which it is carried. This shoe is of such dimensions that it will fit within the 30 groove 22 of the shaft 20 and lie flush with the outer circumference of the said shaft, the inner end of the shoe extending through the bore of the dial and being provided with a lip 29 projecting up in rear of the dial and bearing against the rear side of the same. It will be readily seen that if the dial be rotated, its engagement with the bead 21 will cause it to move longitudinally of the shaft 20 and the pointer will, of course, be turned 40 caused to travel longitudinally of the groove 22 but will be prevented by the walls of said groove from rotating around said shaft with the dial. The dial can, therefore, be turned so as to bring any desired graduation immediately adjacent the end of the indicator and, consequently, set the damper for any desired degree of heat. Inwardly from the scale or graduations a plurality of notches, lugs, or corrugations 30 are provided upon 45 the outer face of the dial concentric therewith whereby as the dial is rotated, the said corrugations will be caused to move under the indicator and engage the same so that the dial will be held against movement in whatever position it may be set. A thumb screw 31 is engaged in the outer end of the shaft 20 so that an exceedingly fine and accurate adjustment of the damper may be had notwithstanding an accumulation of soot and 50 dust upon any of the parts. The lower end of the frame 4 is indented, as shown at 32, to coact with the open lower end of the casing and admit cold air to the hood.

The door 12 consists of a ring properly 55 shaped to fit close over an annular ridge or

lip 33 on the outer side of the hood and defining the door opening, a convex glass 34 being set into the ring. At one side the ring is provided with a loop or eye 35 adapted to fit between similar eyes on a bracket 36 which is secured on the hood, a pin 37 being inserted through the eyes and having a threaded engagement with the lowermost eye to establish a hinged connection, the parts of which will not separate. At its opposite side, the ring or door frame 12 is provided with a lug or projection 38 adapted to ride over the serrated upper edge of a plate 39 projecting from the hood thereby holding the door firmly. 80

The parts are so arranged and proportioned that when the indicator 26 is at zero on the scale 27, the dial will be at the outer end of the shaft 20 and to set the damper for a higher degree of heat sufficient force is applied to the lug or stop 25 to rotate the dial. The rotation of the dial will cause it to travel inwardly upon the shaft 20 until the designation of the desired degree of heat is brought under the indicator when the dial 90 may be permitted to rest. One revolution of the dial will bring the lug 25 against the indicator so that the movement will be limited to the scope of the scale. As the dial passes under the indicator, the nib 40 thereon rides over the corrugations 30 and by its engagement therewith holds the dial in any position in which it may be set. 95

When applying the device, the dial is arranged at the outer end of the shaft 20 and 100 the damper plate 13 should then assume a vertical position and fill the opening in the frame 4. The set screw 31 is then adjusted in or out until the damper plate shows a tendency to rock in its bearings, this regulation adjusting the damper to the height or size of the chimney. The dial is then rotated to set it to the degree of heat desired. 105

It is well known that hot air and gases tend to rise and this tendency increases with 110 the temperature. With the dial set at zero, the damper assumes a vertical position and is balanced so that any increase of temperature within the casing will create a suction at the inner side of the damper and permit 115 it to yield to the pressure of the cold air flowing through the lower end of the hood. This cold air will then, of course, flow past the damper into the casing and check the draft. If the dial be set closer to the damper, 120 the governor arm will overbalance the damper and tend to hold it in closed position so that a greater difference in the temperatures at the opposite sides of the damper will be needed to permit it to open. The 125 difference will, of course, become greater as the dial is set closer to the damper and, consequently, the farther in the dial is moved the hotter the rising gases will be permitted to get before being checked. 130

Having thus described the invention, what is claimed as new is:

1. The combination of an open frame having outwardly diverging side walls, a hood having inwardly extending webs bearing upon the frame adjacent the side walls thereof and having outwardly diverging ribs at the inner edges of said webs to engage the said side walls, the hood being further provided with an internal transverse shoulder near its upper end to rest on the top of the frame, and a damper mounted between the sides of the frame for rocking movement.
2. A damper comprising a plate mounted for rocking movement, a governor arm projecting rearwardly from said plate, a shaft projecting forwardly from the plate, a regulating dial rotatably and slidably mounted upon the shaft, and an indicator coöperating with said dial.
3. A damper comprising a plate mounted for rocking movement, a governor arm projecting rearwardly from the said plate, a shaft projecting forwardly from the plate, a regulating dial mounted on said shaft to rotate about the same and move longitudi-

nally thereon, and an indicator movable along the shaft with the dial but held against rotation.

4. A damper comprising a plate mounted for rocking movement, a governor arm projecting rearwardly from the plate, a shaft extending forwardly through the plate and provided with a longitudinal groove, a regulating dial fitted upon the shaft to rotate about the same and move longitudinally thereof, and an indicator fitting closely to the dial and constructed with a shoe slidably mounted in the groove in the shaft and having an upturned end engaging the rear side of the dial.

5. A damper comprising a plate mounted for rocking movement, a governor arm projecting rearwardly from the plate, a shaft extending forwardly from the plate, a regulating dial rotatably and slidably mounted on the shaft, an indicator movable along the shaft with the dial but held against rotation about the shaft, and holding devices mounted on the dial to engage the indicator.

In testimony whereof I affix my signature.
WILLIAM VERNAL COATE. [L.S.]
